Int. Filing Date: **May 4, 2017**

CLAIM

Int. Reg. No.: **DM/097225**

The ornamental design for a wireless headset communication device with speaker, as shown and described.

Int. Reg. Date: **May 4, 2017**

DESCRIPTION

Int. Reg. Pub. Date: **Nov. 10, 2017**

(30) **Foreign Application Priority Data**

1. Wireless headset communication device with speaker

Nov. 7, 2016 (KR) 30-2016-0053295
